DESIGN FOR A TOY STOVE

Joseph Brunetti, Carlstadt, N. J., assignor to
Columbia Protektosite Co., Inc., Carlstadt, N. J.,
a corporation of New Jersey

Application December 19, 1944, Serial No. 116,996

Term of patent 7 years

(Cl. D34—15)

To all whom it may concern:

Be it known that I, Joseph Brunetti, a citizen of the United States and resident of Carlstadt, in the county of Bergen and State of New Jersey, have invented a new, original, and ornamental Design for a Toy Stove, of which the following is a specification, reference being had to the accompanying drawing, forming a part thereof, and of which Figure 1 is a front view of a toy stove showing my new design; Fig. 2 is a top view thereof; Fig. 3 is a side view thereof; and Fig. 4 is a reduced sectional view taken on the broken line 4—4 of Fig. 1.

Certain lines shown are printed on the toy.

The dominant features of the design in the toy stove shown consist of the sloping central front panel and oven door extending upwardly and inwardly from the broiler door to the centrally located top burner panel as shown.

I claim:

The ornamental design for a toy stove, substantially as shown and described.

JOSEPH BRUNETTI.
